CLAIM

The ornamental design for a handle for a toothbrush, as
shown and described.

DESCRIPTION

FIG. 1 is a perspective front view of a handle for a
toothbrush showing my new design;

FIG. 2 is a front view thereof;

FIG. 3 is a back view thereof;

FIG. 4 is a left side view thereof; and,

FIG. 5 is a right side view thereof.

The contrast in shading techniques merely represents a
contrast in appearance and no specific colors, materials, or
textures are claimed. The broken line schematic showing of
the head is for illustrative purposes only and forms no part
of the claimed design.
